ROTARY CONDUCTION BRANDING UNIT

John Stoyan, East Kildonan, Manitoba, Canada,
assignor to Canada Packers Limited, St. Boni-
face, Manitoba, Canada

Application December 13, 1934, Serial No. 757,414
In Canada November 24, 1934

1 Claim. (Cl. 219—30)

This invention relates to improvements in rotary conduction branding units and an object of the invention is to provide a branding iron of this type which may be suspended over the table on which the object to be branded lies, and by rolling said branding iron over the object, will cause the rind of a carcass or other object to be seared with a branded mark.

A further object of my invention is to provide a branding iron of this character with which the operation of branding may be continuously performed and which will not require frequent periods of inactivity for reheating purposes.

A further object of my invention is to provide a branding iron of this character which can be easily repaired and will not readily become out of order.

A further object of this invention is to provide a branding iron of this character which may be operated upon a 220 volt circuit or a 110 volt circuit.

With the foregoing more important objects in view, and such other objects as may appear as the specification proceeds, my invention consists primarily in the arrangement and construction of parts, all as hereinafter more particularly described, reference being had to the accompanying drawings, in which:—

Fig. 1 is a plan view of my rotary conduction branding iron.

Fig. 2 is a side view of Fig. 1.

Fig. 3 is an extended perspective view of the principal component parts of my rotary conduction branding iron.

Fig. 4 is a schematic diagram of the series hook-up for my rotary conduction branding iron.

Fig. 5 is a schematic diagram of the alternative parallel hook-up for my rotary conduction branding iron.

Fig. 6 is a diametrical section through my branding wheel.

Fig. 7 is a diametrical section through my face plate.

In the drawings like characters of reference indicate corresponding parts in the different figures.

My rotary conduction branding iron consists of a branding wheel A centrally bored and carried upon a shaft B. Upon either side of the branding wheel, are spiders 1 and 2, these spiders being each provided with a bearing boss 3 and 4. The spiders and bosses are suitably keyed to the shaft to prevent rotation thereof and the central drilling of the branding wheel is journaled upon the boss 3.

The branding wheel is composed of a thin metallic central disc 5 and an outer annulus 6. Markings 7 are incised in relief upon this annulus and the annulus itself may be shrunk, welded or otherwise attached to the disc 5. This portion being considerably thicker in cross section than the disc 5, it follows that the central portion is recessed upon either side as at 8 and 9. Two pairs of circular elements are mounted within the recesses 8 and 9, these elements being enclosed in pairs of casings 10 and 11.

A pair of heat radiation discs 12 and 13 are journaled upon the bosses 3 and 4 with their inner faces in contact with the element casings 10 and 11.

A pair of insulating discs 14 and 15 are journaled upon the bosses 3 and 4 with their inner faces in bearing contact with the heat radiation discs 12 and 13, the aforementioned assembly being compacted by the arms 16 of the spiders 1 and 2. At the outer side of the spider 2 is mounted an insulating face plate 17, this face plate being inlaid with a pair of metallic slip rings 18 and 19. Bolts 20 extend through the various orifices 21 in the face plate, spiders, insulation discs, heat radiation discs and the branding wheel disc in order to hold these parts firmly together as they rotate.

Terminals 22 are located upon the inner side of the face plate 17 and further terminals 22a upon the outer side of the element casings 10 and 11. Electrical leads 23 extend between the terminals upon the face plate and the terminals upon the element casings, these being led through the various apertures 24, 25 and 26 upon the various discs and through the channels 27 upon the outer faces of the insulating discs 14 and 15.

The shaft with the mounted assembly just described, is journaled in a pair of opposed yokes 28, upon which is located a pair of opposed handles 29. A lateral slide bar 30 extends upwardly and laterally over the branding assembly, this slide bar being of an arcuate form. A split shackle 31 or some suitable form of swivel union is freely attached to the slide bar to enable the assembly to be suspended upon a counterweight arm above the branding table.

A pair of collars 32 are mounted upon the shaft B upon either side of the rotary assembly and within the confines of the yoke 28 in order to prevent lateral movement of the assembly.

I may elect to journal the ends of my shaft upon simple opposed bearing orifices formed in the yoke but in the drawings I have shown a pair of externally threaded bushings 33 upon

which the shaft is journaled, the threads of these bushings being received into corresponding threads in the opposed orifices of the yoke. The bushings will be prevented from slackening off by 5 means of jam nuts 34.

To establish contact between a source of electrical power and the unit, I provide contact brushes 35 which are spring seated in a pair of nipples 36 screwed into the yoke to one side of 10 one of the collars 32 and in alignment with the slip rings 18 and 19.

The terminals 22 upon the element casings 10 and 11 are in pairs. This is to enable a parallel connection to be used if desired. When a series 15 connection is used, current passes from the element on one side of the disc 5 to the element upon the other side by means of the beaded leads 37 and 38.

In the drawings, I have shown the resistance 20 wires as spirally formed within the element casings 10 and 11. Obviously, however, they may be wound in any manner therewithin which I may elect, and it will be noted that these wires within the element casings are insulated therefrom by 25 means of heat conducting insulation 39 shown in Fig. 6.

The reason for the provision of heat radiation discs 12 is in order that the heat emanating from the elements 10 and 11 may be all directed up- 30 wardly so as to concentrate an intense heat upon

the incised branding surface. Due to the fact that the outer faces of these heat radiation discs 12 and 13 bear against insulating discs 14 and 15, the heat cannot dissipate in any direction except to the surface of the branding wheel. 5

Since various modifications can be made in the above invention, and many apparently widely different embodiments of same made within the scope of the claim, without departing from the spirit and scope thereof, it is intended that all 10 matter contained in the accompanying specification shall be interpreted as illustrative only and not in a limiting sense and I desire only such limitations placed thereon as are specifically expressed in the accompanying claim. 15

What I claim as my invention is:—

A rotary branding unit heated by electrical conduction comprising a circular heat conducting element, a branding surface surrounding said element, resistances mounted upon both sides of 20 said heat conducting element, heat conduction plates upon the outer side of said resistances, heat insulation members upon the outer side of said plates, a shaft extending through said branding unit, means comprising slip rings and brushes 25 for introducing electric current to said resistances, a yoke surrounding said unit and freely mounted upon said shaft and means for manually operating said unit over the object to be branded. 30

JOHN STOYAN.
